UNITED STATES PATENT OFFICE.

WILLIS S. CRANDELL, OF ELSMERE, NEW YORK, ASSIGNOR TO A. P. W. PAPER CO., OF ALBANY, NEW YORK, A CORPORATION OF NEW YORK.

PAPER-MAKING MACHINE.

Application filed May 9, 1919. Serial No. 295,828.

To all whom it may concern:

Be it known that I, WILLIS S. CRANDELL, a citizen of the United States, residing at Elsmere, in the county of Albany and State 5 of New York, have invented a certain new and useful Paper-Making Machine, of which the following is a specification.

The object of my invention has been to provide a paper making machine, which 10 shall have among other advantages, that of having a gearing for driving the wet press, the driers, and the calenders or other parts of the machine requiring to be driven synchronously, so that the speed of any one or 15 more of them may be exactly regulated to prevent breaking of the web of paper, and which mechanism shall be simple in the mode of adjustment to bring the speed of the various parts in unison and shall be de- 20 pendable so as to reduce to a minimum the accidents which might happen from such mechanism which would cause a stoppage of the machine, and which mechanism shall require but comparatively little power to 25 drive it, and to such ends my invention consists in the paper making machine hereinafter specified.

In the accompanying drawings I have illustrated my invention by its application 30 to that type of paper making machine known as a "cylinder" machine and by the best form of mechanism known to me. My invention is capable of use with any type 35 of paper making machine and the driving mechanism can be embodied in many different forms, and my invention is, therefore, not to be restricted to the form disclosed in this application, but such form shall be regarded only as typical of many possible em- 40 bodiments.

Fig. 1 is a plan view of the paper-making machine from the center to the left-hand end thereof;

Fig. 2 is a vertical side elevation of the 45 parts shown in Fig. 1;

Fig. 1^a is a plan view of the machine from the center to the right-hand end thereof;

Fig. 2^a is a vertical side elevation of the parts shown in Fig. 1^a;

Fig. 3 is a detailed view, partly in section, along the line 3—3 of Fig. 1^a of the co-operating parts comprising the gear adjusting means, the hand wheel and its shaft for manually adjusting the gear being shown in 50 elevation;

Fig. 4 is a longitudinal sectional view of the parts assembled as in Fig. 3, with certain of these parts shown in elevation for clearness;

Fig. 5 is a view partly in longitudinal 60 section, showing the slidable mounting for one of the cone gears.

Paper making machines comprise broadly apparatus for forming the fiber into a wet sheet or web by depositing the fiber from a 65 body of water upon a web-forming carrier, which apparatus is made in many different forms, press rolls which express from the web as much water as possible, driers for 70 drying the paper, and calenders for compressing and finishing the paper.

It is imperative that the rate of travel of the web through the press rolls, the driers, and the calenders, should be the same, because if one of them causes the web to travel, 75 for instance, a little faster than the others, this will gradually cause the web to be stretched until it will sooner or later break. In the illustrated embodiment of my invention, to accomplish the said purposes, which 80 is shown in the accompanying drawings the press 1 is at the right hand end of the machine, the driers 2 are in the center, and the calenders 3 are at the left hand end. I provide the machine with a shaft 4 which may 85 consist of a single piece of shafting or of a number of pieces coupled or geared together so that in effect they constitute a single piece of shafting. This shaft may be driven by any desired motor, and, in the 90 present instance, I have illustrated it as driven by an engine 5. The press comprises a pair of "squeeze rolls" 6, one of which has a shaft 7 by which it may be turned or driven and a pair of "press rolls" 8, said two 95 pairs of rolls being used to express as much water from the newly formed web 9 as possible by the use of mere pressure. The lowermost press roll is driven by a shaft 9^c which receives its motion from a shaft 10 by 100 means of a gear 9^a and a pinion 10^a. The shafts 7 and 9^c are in the present instance shown as having pulleys 7^a and 9^b which are connected by a belt 11. The shaft 10 is mounted in stationary bearings, and carries 105 a friction cone 12 by which it is driven. The cone 12 is driven by a cone 13 which is splined upon the shaft 4. The cone 12 is splined upon the shaft 10 so as to be slid- 110 able longitudinally thereon and at the same

time to be rotatable therewith. Slidingly journalled in the bearing of the shaft 10 and immediately surrounding the shaft, is a sleeve 12^a, having one end abutting the hub 5 of the cone 12. Between the other end of the sleeve 12^a and the gear 10^a fixed on the shaft 10 (Fig. 5), is a spring 12^a. It is apparent from the construction thus described and shown that the cone 12 is yieldingly 10 forced outwardly always in contact with the cone 13, and that the cone 12 is permitted the necessary sliding movement upon the shaft 10 to maintain such contact in the various adjusted positions of the cone 13. In 15 the present instance the cone 13 is mounted upon a sleeve 13^a, which is, itself, splined upon the shaft 4, and the said sleeve is engaged by a screw 13^b as clearly shown in Figs. 3 and 4 which is mounted in a stationary 20 part, such as a pedestal 14, and the screw is turned by a hand-wheel 15, as by a worm on the shaft of the hand-wheel and a worm-wheel mounted on the screw. This mechanism enables the cone 13 to be shifted 25 along the shaft 4, the preferably yielding surfaces or mounting of at least one of the two cones permitting the consequent relative change of the position thereof. The shifting of the cone 13 decreases or increases 30 the radius of the mean circle or "pitch line" upon which it engages the large cone and consequently drives the large cone at a higher or lower rate of speed.

By similar driving mechanisms motion is 35 adjustably transmitted from the shaft 4 to the first drier 2^a, to driers 2^b near the center of the series of driers, and to the calenders 3.

By means of the mechanism, one embodiment 40 of which I have described, the surface speeds of the various rolls, driers, and calenders engaging the web of paper can be made absolutely the same so that there will be no creeping of the paper, and the breakage 45 of the paper can thereby be avoided. The mechanism being driven by what can be actually, or in effect, a single shaft, and without the intervention of belts throughout that portion of the machine where the web is 50 relatively dry and cannot stretch without breaking, is so simple that comparatively little power is required to drive it. Such mechanism has also proven in actual practice to be so reliable that the machine is very 55 seldom required to be stopped on account of anything getting out of order in connection with the mechanism. Thus the mechanism results in an increased output of paper

by the machine, and in a material saving 60 of the power required to drive it.

By the term "directly connected" appearing in the claims is meant such a connection between the variable speed mechanism and the long shafts by which they are driven 65 as to avoid the use of belts or similar forms of driving mechanisms.

I claim:

1. In a paper making machine, a plurality of machine elements adapted to perform successive operations in making a paper web, and an adjustable mechanism for driving 70 said elements at the desired relative speeds, said mechanism comprising a line shaft extending longitudinally of the machine, friction cones carried by said line shaft respectively adjacent said elements, means permitting each of said cones to slide longitudinally relative to the line shaft as a whole, friction gears respectively engaging 75 said cones, means for transmitting motion from said gears to their respective machine elements, and means for adjusting the longitudinal position of each of said cones relative to the line shaft as a whole, to vary the speed ratio between the line shaft and corresponding machine elements. 80

2. The combination set forth in claim 1, wherein said friction gears are mounted upon intermediate shafts extending transversely between the machine and said line 90 shaft. 95

3. In a paper making machine, a plurality of machine elements adapted to perform successive operations in making a paper web, an adjustable mechanism for driving 95 said elements at the desired relative speeds, said mechanism comprising a line shaft extending longitudinally of the machine, friction gears carried by said line shaft respectively adjacent said elements, means permitting each of said cones to slide longitudinally relative to the shaft as a whole, friction gears respectively engaging 100 said cones, means for transmitting motion from the gears to their respective machine elements, and a screw adjusting device for shifting the longitudinal position of each of said cones relative to the line shaft as a whole to vary the speed ratio between the line shaft and the corresponding machine 105 elements. 110

In testimony that I claim the foregoing, I have hereunto set my hand this 24th day of April, 1919.

WILLIS S. CRANDELL.
